UNITED STATES PATENT OFFICE.

DAVID LEE, JR., OF MOUNT WILLING, ALABAMA.

COMBINED CANE AND CIGAR-CASE.

SPECIFICATION forming part of Letters Patent No. 295,654, dated March 25, 1884.

Application filed November 16, 1883. (No model.)

To all whom it may concern:

Be it known that I, DAVID LEE, Jr., of Mount Willing, Lowndes county, Alabama, have invented a new and Improved Combined 5 Cane and Cigar-Case, of which the following is a full, clear, and exact description.

The object of my invention is to provide a new and improved cane in which a quantity of cigars and matches can be carried.

10 The invention consists in a hollow cane containing a tube adapted to receive a number of cigars, which are pressed upward and outward by a spiral spring in the bottom of the tube, the uppermost cigar being held by springs secured in the upper end of the tube. A cap adapted to receive matches is hinged to the upper end of the cane.

Reference is to be had to the accompanying drawings, forming part of this specification, in 20 which similar letters of reference indicate corresponding parts in all the figures.

Figure 1 is a longitudinal sectional elevation of my improved combined cane and cigar-case. Fig. 2 is an enlarged longitudinal sectional elevation of the upper part of the cane, showing the match-receiving cup opened. Fig. 3 is a top view of the cane, showing the match-receiving cup opened. Fig. 4 is a horizontal sectional view of the cane on the line *x* 25 *x*, Fig. 1; and Fig. 5 is a horizontal sectional view on the line *y* *y*, Fig. 1.

The cane *A*, which is made hollow, is adapted to receive a tube, *B*, having its lower end open, which tube is provided at its upper end with suitable notches for holding it in place in the cane in such a manner that it can be removed very easily. In the bottom of the cane a spiral spring, *C*, is placed, and at the upper end two springs, *D*, are soldered or otherwise secured 35 to the inner surface of the tube. The upper ends of the spring *D*, which are pressed toward each other, are concaved, so as to fit closely against a cigar. To the upper end of the cane a hollow cap, *E*, is hinged, the lower 40 end of which can be closed by a laterally-swinging plate, *F*, pivoted to the bottom of the cap. The cap *E* is to receive the matches,

and the plate *F* is to prevent the matches from dropping out. The cane is provided with a spring-catch, *G*, for locking and holding the 5 cap on the cane by simply swinging the cap down on the upper end of the cane.

The tube *B* is withdrawn, and is then filled with cigars and inserted in the hollow cane, whereby the spring *C* will be compressed. 5. The spring *D* rests against the uppermost cigar, and prevents it from being thrown entirely out of the tube by the spring *C*. If a cigar is desired, the cap *E* is swung back to uncover the upper end of the cane, and a cigar is 60 seized and withdrawn from the tube. As soon as a cigar is withdrawn the rest are pushed upward by the spring *C*.

Having thus described my invention, I claim as new and desire to secure by Letters Patent— 65

1. The combination, with a hollow cane adapted to receive cigars, of a spiral spring secured in the bottom of the hollow or recess in the cane, substantially as herein shown and described, and for the purpose set forth. 7C

2. The combination, with a hollow cane, of a removable tube fitting in the same, and of a spiral spring, substantially as herein shown and described, and for the purpose set forth.

3. The combination, with the cane *A*, of 75 the tube *B*, the spiral spring *C* at the bottom, and the springs *D* at the top of the tube, substantially as herein shown and described, and for the purpose set forth.

4. The combination, with the cane *A*, of 80 the tube *B* and the pivoted cap *E*, forming a match-receptacle, substantially as herein shown and described, and for the purpose set forth.

5. The combination, with the cane *A*, of 85 the tube *B*, the hinged cap *E*, and the plate *F*, pivoted to the bottom of the said cap, substantially as herein shown and described, and for the purpose set forth.

DAVID LEE, JR.
